UNITED STATES PATENT OFFICE.

WILLIAM EDWARD COTTRELL, OF TIPTON, IOWA.

DESIGN FOR A HORSESHOE-CALK.

SPECIFICATION forming part of Design No. 32,345, dated March 13, 1900.

Application filed February 16, 1900. Serial No. 5,537. Term of patent 14 years.

To all whom it may concern:

Be it known that I, WILLIAM EDWARD COTTRELL, a citizen of the United States, residing at Tipton, in the county of Cedar and State of Iowa, have invented and produced a new and original Design for a Horseshoe-Calk, of which the following is a specification.

This invention relates to a new and useful design for a horseshoe-calk; and the essential features reside in a compound elliptical body of tapered form having a curved head intermediate of said body and a cylindrical shank and lower conical projections.

In the drawings, Figure 1 is a perspective view of a horseshoe-calk embodying the features of the design. Fig. 2 is a horizontal section on the line 2 2 of Fig. 1 looking in the direction of the arrows.

The numeral 1 designates a tapered com-

pound elliptical body having diametrically disposed entrant angular recesses 2. The body 1 has a curved edge 3, which projects over the same, and from the side of the head opposite that with which the body 1 connects a cylindrical shank 4 extends, and from the lower reduced portion of the body 1 project conical teeth 5.

Having thus described the invention, what is claimed as new is—

The design for a horseshoe-calk, herein shown and described.

In testimony that I claim the foregoing as my own I have hereto affixed my signature in the presence of two witnesses.

WILLIAM EDWARD COTTRELL.
